UNITED STATES PATENT OFFICE.

JAN WOLSKI, OF CHICAGO, ILLINOIS.

AUTOMATIC STATION-INDICATOR FOR CARS.

1,155,694.

Specification of Letters Patent.

Patented Oct. 5, 1915.

Application filed November 30, 1914. Serial No. 874,686.

To all whom it may concern:

Be it known that I, JAN WOLSKI, subject of the Czar of Russia, residing at Chicago, in the county of Cook and State of Illinois, have invented certain new and useful 5 Improvements in Automatic Station-Indicators for Cars, of which the following is a specification.

This invention relates to certain new and 10 useful improvements in automatic station indicators for cars.

The primary object of the device is to provide an indicating means within a car 15 trip-operated exteriorly of the car whereby the names of the successive stations along the route traveled is automatically changed.

A further object is to provide a tripping member upon the car roof adapted to engage a fixed actuator at a desired distance 20 from a station and whereby such mechanism shifts a curtain within the car for displaying to the occupants thereof the name of the next station to be reached during the travel of the car.

A still further object is to provide a special 25 form of automatic shifting means for a station-indicating curtain whereby the curtain will be shifted in opposite directions automatically when the carrying car is traveling in opposite directions.

With these general objects in view and others that will appear as the nature of the invention is better understood, the same 30 consists in the novel combination and arrangement of parts hereinafter more fully described, illustrated in the accompanying drawings and set forth in the appended claim.

In the drawings forming a part of this 35 application and in which like-designating characters refer to corresponding parts throughout the several views, Figure 1 is a side elevation of the device attached to a car roof, the roof being broken away 40 and the forward side of the casing removed.

Fig. 2 is a central transverse vertical sectional view of the elements shown in Fig. 2. Fig. 3 is a similar section taken through the casing of the operating mechanism and 45 a portion of the trip wheel being broken away. Fig. 4 is an enlarged detail front elevation of the lower portion of the winding drum and its actuating means, parts being broken away. Fig. 5 is an enlarged 50 sectional detail view of one of the dog actuators for the winding drum shaft, and

Fig. 6 is a horizontal sectional view showing in enlarged detail the operative engagement between the dog actuator and the drum shaft.

Referring more in detail to the drawings, the invention broadly consists in the provision of a casing 10 suspended interiorly of the roof 11 of a car such as 12 and provided with a shiftable curtain or apron 13 which has the names 14 of the stations along the line of travel of the car printed upon the directly opposite sides thereof, the name of a single station being visible to the occupants of the car through opposite 65 windows 15 of the adjacent portions 16 of the sides 17 of the said casing.

The casing 10 is divided into two portions or chambers, one portion 18 being adapted for holding the curtain which is wound 70 upon and extends between upper and lower winding drums 19 and 20 respectively, while the other chamber 21 positioned at the side of the portion 18 is adapted for housing the actuating mechanism for the drums, 75 it being noted that the axles 22 and 23 respectively of the drums 19 and 20 are journaled in the opposite side walls 24 and 25 of the casing portion 18 and have extending ends 26 and 27 respectively extending into 80 the portion or chamber 21 of the casing as best illustrated in Fig. 2.

Pulley wheels 28 are mounted upon the said ends 26 and 27 of the axles and have a belt 29 running thereover whereby the 85 forced turning of the lower axle 23 by the mechanism hereinafter described, imparts a corresponding movement to the upper axle 22 and by means of which the two drums are turned simultaneously in the desired direction for shifting the indicating curtain 13.

Housings 30 are journaled upon the axle extension 27 and are of the form best illustrated in Figs. 5 and 6 of the drawings, each being provided with a pivoted dog 31 100 having a curved tapered end 32 normally engaging the teeth of the adjacent toothed portion 33 of the said axle end 27. Each housing is provided with a longitudinally extending leaf spring 34 having one end rigidly secured as at 35 to the housing adjacent the shaft journal end thereof and having its free end resiliently engaging the adjacent face of the dog 31 for normally retaining the dog in engagement with the shaft teeth. 105 The dogs 31 are pivoted upon pins 36 carried by the housings 30 and are each pro-

vided with an angular extension 37 for pivotal connection with actuating rods 38. The dogs 31 are arranged for engaging the teeth upon the opposite sides of the shaft or axle 5 extension 27, it being noted that the toothed portions 33 are slightly separated from each other and have the teeth thereof inclined in opposite directions. By this arrangement it will be seen that an upward pull upon either 10 of the rods 38 will turn its housing 30: and, the carried dog 31 being in engagement with the axle, the latter will be turned thereby, while the return or downward movement of the rod 38 allows its housing to return to its 15 normal vertical position, during which movement the dog ratchets over the teeth of the axle allowing the axle and the drums to remain in the adjusted position. An encircling spring 39 is provided for each of 20 the rods 38, the said springs having their lower ends seated upon and secured to a horizontal brace 40 of the chamber 21, through the openings 52 of which the rods 38 extend, while their upper ends are secured to the said rods and by which means as will be evident, the rods will be automatically returned to their rest positions, while a stop 51 is engaged by the housings to position said housings normally vertical. 25 A bracket 41 mounted upon the outside of the car roof 11 has a shaft 42 journaled therein and provided at one end with a peripherally grooved wheel 43 over which a cord 44 passes and has depending ends 45 30 of equal length running between spaced rollers 46 and secured to the upper ends of the rods 38. The said cord is secured at its central point by a hold-fast device 47 to the periphery of the wheel 43.

40 A V-shaped trip arm 48 is secured to the end of the shaft 42 opposite the pulley 43 and is adapted to be engaged by stationary trip bars positioned at each station throughout the line of travel of the car. The V-shaped trip arm permits of a swing of greater length than would an ordinary vertical single arm, this increased movement being imparted to the travel of the web 13. 45 From this detailed description of the device, it will be seen that with the mechanism positioned so that the next station to be reached by the car will be visible through the opposite windows 15, the arm 48 will engage the bar 49 when such station is 50 reached, which will result in turning the shaft 42 in a rocking movement and thus turning the pulley 43 which will pull up-

wardly upon one of the cord ends 45 and consequently move the rod 38 upwardly which is attached thereto, thus shifting its 60 dog and housing as well as the axle end 27 which shifts the curtain 13 sufficiently to place the name of the next succeeding station viewable through the windows 15, while the actuating mechanism is then returned by 65 means of its spring 39 to its normal rest position as illustrated in Figs. 4 and 6. As one of the actuating dogs and rods is adapted to wind up the curtain in one direction, and the other similar means to wind the 70 same in the opposite direction, it will be noted that the correct succeeding stations will be indicated upon the outward trip of the car by one of the shifting devices, while the other device will shift the curtain upon 75 a return trip. The device will operate in a similar manner if only a portion of the complete trip is taken and the car then returned without traveling to the end of the line, the car being of the type that travels 80 in either direction desired without being turned around.

As herein illustrated, the window sides 17 of the casing are preferably provided with the V-shaped walls 16 having the windows 15 at their apices, while pairs of rollers 50 are positioned within the casing for accurately conducting the curtain between the two windows.

While the form of the invention herein 90 shown and described is what is believed to be the preferred embodiment thereof it is nevertheless to be understood that minor changes may be made without departing from the spirit and scope of the invention as 95 claimed.

What I claim as new is:—

In a device of the kind described, a shaft, oppositely-disposed ratchets on the shaft, independent levers loosely journaled on the 100 shaft and freely movable in opposite directions, stops to limit movement of each lever in the opposite direction to that in which it is freely movable, pawls carried by the levers and engaging the ratchets, and means 105 connecting the free ends of the levers and including a flexible portion.

In testimony whereof I affix my signature in presence of two witnesses.

JAN WOLSKI.
